UNITED STATES PATENT OFFICE

EDWIN W. SEEGER, OF SOUTH MILWAUKEE, WISCONSIN, ASSIGNOR, BY MESNE ASSIGNMENTS, TO CUTLER-HAMMER INC., OF MILWAUKEE, WISCONSIN, A CORPORATION OF DELAWARE

MOTOR CONTROLLER

Application filed March 29, 1926. Serial No. 98,118.

This invention relates to improvements in motor controllers and more particularly to shunt field controllers for direct current motors.

5 An object of the invention is to provide simplified means for effecting step by step commutation of the resistance to be included in or excluded from the shunt field circuit.

Another object is to provide for control of 10 said resistance through a plurality of switches of like construction, means being provided for insuring operation of the respective switches in proper sequence to effect a graduated increase or decrease in the 15 strength of the shunt field.

Another object is to provide simple and efficient means for imparting an appreciable time element of response in the operation of the individual switches controlling the 20 respective sections of resistance in the shunt field circuit.

Other objects and advantages of the invention will hereinafter appear.

In the drawing I have illustrated certain 25 embodiments which my invention may assume in practice and the same will now be described, it being understood that the invention may assume other forms falling within the scope of the appended claims.

30 In the drawing,

Figure 1 is a schematic and diagrammatic illustration of a controller embodying the invention; and

Fig. 2 similarly illustrates a modified form 35 of controller constructed in accordance with the invention.

Referring to Fig. 1, A designates the armature of a compound wound direct current motor, the series field winding thereof being indicated at F and the shunt field winding thereof being indicated at F¹. The armature A and series field F are adapted to be connected across lines L¹, L², by any suitable form of starting switch, the electroresponsive starting switch S as shown being provided with a plurality of movable contact elements or fingers 5, 6 and 7 for engagement with stationary contacts 8, 9 and 10 to initially include in and sequentially exclude from the armature and series field circuit suitable steps

of starting resistance R and R¹. Switch S is normally biased to open position, and the same is provided with an operating coil 11, the energizing circuit of which is completed upon movement of the contactor 12 of a 55 manual control switch MC into engagement with the contact segment 13, as shown in dotted lines at a. Switch S is also preferably provided with a dashpot device 14 for retarding the movement of contact fingers 5, 6 and 7 60 into and out of engagement with contacts 8, 9 and 10, respectively.

During starting of the motor in the manner aforescribed full strength of the shunt field F¹ is provided through normally closed 65 positioning of contacts 15, 16 and 17 of electroresponsive switches S², S³ and S⁴, respectively, whereby the shunt field weakening resistance sections R², R³ and R⁴ are short-circuited. Switches S², S³ and S⁴ are 70 respectively provided with operating coils 18, 19 and 20.

Thus, to effect high speed operation of the motor after attainment of normal speed 75 thereof, arm 12 of switch MC may be moved to dotted line position b, into engagement with contact segment 21, thereby providing an energizing circuit for coil 18 of switch S². Contact 15 thereupon opens to interrupt the short-circuit around resistance section R² and 80 coil 19. Resistance R² and coil 19 will thus be included in circuit in series with each other and in series with shunt field F¹. Contact 16 then opens due to operating energization of coil 19, whereby resistance sections R² and R³ 85 and coils 19 and 20 are connected in series with each other and in series with field F¹. In like manner coil 20 effects opening of contact 17 whereby each of the resistances R², R³ and R⁴ and the associated coils 19 and 20 are 90 included in circuit in series with field F¹.

By the arrangement aforescribed an appreciable time interval elapses between opening of the respective contacts 15, 16 and 17 of switches S², S³ and S⁴ due to the inherent time 95 lag incident to the inductance of the coils 18, 19 and 20 thereof. In other words, the inductive effect of the shunt field winding F¹ is utilized to increase the time element of response of switches S³ and S⁴ without necessi- 100

tating an increase in the size of the operating coils 19 and 20 of the latter and without necessitating addition of any elements whatsoever to the control mechanism. Inclusion of resistance sections R^2 , R^3 and R^4 in positive steps is thus insured. Moreover, an effective but less pronounced time element of response of switches S^2 , S^3 and S^4 is provided during the operation of excluding resistance sections R^2 , R^3 and R^4 from the circuit of field F^1 . Thus, upon movement of arm 12 from dotted line position b to position a the energizing circuit of coil 18 is interrupted, which effects simultaneous short-circuiting of resistance section R^2 and coil 19 through reclosure of contact 15. The consequent reclosure of contact 16 effects simultaneous short-circuiting of resistance section R^3 and coil 20, whereas subsequent reclosure of contact 17 effects short-circuiting of resistance section R^4 ; field F^1 being then connected directly across lines L^1 , L^2 through contacts 15, 16 and 17. The motor will then run at normal speed pending movement of contact 12 of switch MC to the full line position shown, which results in deenergization of coil 11 of switch S. Contacts 7, 6 and 5 will thereupon open sequentially to first reinclude resistance section R^1 in circuit, then sections R^1 and R, and then effect opening of the armature circuit through disengagement of contacts 5 and 8.

By the arrangement aforescribed I provide for simple and positive control of the shunt field acceleration and deceleration, the means employed being operable automatically to insure the desired time element of response thereof without the use of electrical interlocks.

The construction illustrated in Fig. 2 is in many respects substantially like that shown in Fig. 1, and corresponding parts have been given like characters of reference. It will be noted, however, that the electroresponsive switches S^{12} , S^{13} and S^{14} of Fig. 2 are of the normally open type, the normally open contacts thereof being designated by numerals 22, 23 and 24, respectively. Said switches are provided with operating coils 18, 19 and 20, respectively; and the contact segment 21 controlling coil 18 is arranged to be engaged by contactor 12 upon movement of the latter to dotted line position a .

In this manner the contacts 22 of switch S^{12} are adapted to be closed substantially simultaneously with the closure of contacts 5 and 8 of starting switch S and upon closure of said contacts 22 coil 19 will be connected across resistance section R^2 , thereby short-circuiting the latter. With coil 19 thus energized closure of contacts 23 of switch S^{13} is effected to include coil 20 in circuit across resistance section R^3 , thereby short-circuiting the latter. The resulting energization of coil 20 effects closure of contacts 24 to short-circuit resist-

ance section R^4 , whereupon shunt field winding F^1 will be connected directly across the line through contacts 22, 23 and 24 and coils 19 and 20. In this way the shunt field F^1 is strengthened in several steps at the start, thus smoothing out the acceleration. 76

When the motor is brought to normal speed through closure of contacts 6-9 and 7-10 of the starting switch S, the speed thereof may be increased by movement of contactor 12 of switch MC to the dotted line position b . This effects interruption of the energizing circuit of coil 18 of switch S^{12} , and the contacts 22 of the latter in opening effect reinclusion of resistance section R^2 in circuit with field F^1 . Contacts 22 in opening also effect interruption of the energizing circuit of coil 19 of switch S^{13} , whereupon the contacts 23 of the latter in opening effect reinclusion of resistance section R^3 in circuit in series with field F^1 and resistance section R^2 . Contacts 23 in opening also effect interruption of the energizing circuit of coil 20 of switch S^{14} , whereupon the contacts 24 of the latter are opened to effect reinclusion of resistance section R^4 in circuit in series with field F^1 and resistance sections R^2 and R^3 . 80 85 90 95

Moreover, deceleration of the motor to normal speed may be effected by reverse movement of contactor 12 to dotted line position a , resulting in sequential exclusion of resistance sections R^2 , R^3 and R^4 from the circuit of shunt field winding F^1 through sequential reclosure of contacts 22, 23 and 24, as will be obvious; the aforescribed time element of response of the switches being insured through the inductive effect of the coils thereof and the inductance of the shunt field winding. That is to say, upon closure of contacts 22 of switch S^{12} to short circuit resistance R^2 the inductance of field winding F^1 will appreciably increase or augment the time element of response of switch S^{13} . Thus with field F^1 in an initially weak condition due to inclusion of resistances R^2 , R^3 and R^4 100 in series therewith, obviously upon exclusion of resistance section R^2 the inductance of winding F^1 will retard or oppose passage of the increased value of current therethrough. Since the building up of the value of current traversing winding F^1 is thus retarded and since the switch winding 19 is then included in series with winding F^1 , it follows that the increase in value of current traversing winding 19 is likewise retarded, with consequent augmentation of the time element of response of switch S^{13} . Closing operation of switch S^{14} is retarded in a like manner. 110 115 120

Similarly, upon movement of contactor 12 from dotted line position a to the full line position illustrated, the contacts 7-10, 6-9 and 5-8 will be opened in sequence to first reinclude resistance R^1 in circuit, then reinclude resistance R and R^1 , and then inter- 125 130

rupt the armature and series field circuit connections.

Such full line positioning of contactor 12 likewise results in de-energizing coils 18, 5 19 and 20 in sequence, whereby the contacts 22, 23 and 24 are returned to their initially open or field weakening positions. The control elements are thus automatically reset for the cycle of operation aforescribed.

In practice the contacts of switches S², S³ and S⁴ in Fig. 1 are of the spring closed type, whereas by the arrangement illustrated in Fig. 2 the use of the spring closed type of contact is obviated. As aforeindicated, positive 15 commutation of the shunt field resistance in steps is effected without requiring the use of electrical interlocking relays or contacts.

What I claim and desire to secure by Letters Patent is:

1. In a device for controlling the shunt field strength of direct current motors, the combination with a shunt field winding and a plurality of resistance sections to be included in or excluded from the circuit of said winding, of a plurality of electroresponsive switches to control said resistance sections, and means for insuring operation of said switches in a predetermined sequence, said 25 means comprising a member operable by the winding of each of said switches for jointly controlling one of said resistance sections and the energizing circuit of the next succeeding electroresponsive switch, each of said 30 energizing circuits respectively including in series therewith said shunt field winding.

2. In a device for controlling the shunt field strength of direct current motors, the combination with a shunt field winding and 40 a plurality of resistance sections to be included in or excluded from the circuit of said winding, of a plurality of electroresponsive switches to control said resistance sections, said switches each having an inherent 45 time element of response for effecting opening or closing of the contacts thereof, and means for utilizing said time element of response of said switches to insure sequential commutation of said resistance sections with 50 respect to the shunt field winding, said means comprising circuit connections whereby each 55 of said switches upon response thereof is adapted to control one of said resistance sections and the operating coil of the next succeeding switch, certain of said operating coils when energized being connected in series with said shunt field winding.

In witness whereof, I have hereunto subscribed my name.

EDWIN W. SEEGER.
